UNITED STATES PATENT OFFICE.

REINHOLD BUKOW, OF ASTORIA, LONG ISLAND, NEW YORK, ASSIGNOR TO HARDMAN, PECK & CO., A CORPORATION OF NEW YORK.

TRACKING DEVICE.

Application filed December 30, 1921. Serial No. 525,900.

To all whom it may concern:

Be it known that I, REINHOLD BUKOW, a citizen of the United States, and resident of Astoria, Long Island, have invented certain new and useful Improvements in Tracking Devices, of which the following is a specification.

My invention relates to improvements in tracking devices for player pianos and similar instruments, by which the tracking mechanism not only retains the correct register between the music sheet and the tracker, but also accommodates itself to variations in width of the music sheets.

15 The accompanying drawings illustrate different embodiments of my invention.

Fig. 1 is a plan of a music spool and related parts;

Fig. 1^a is a fragmentary elevation of the 20 adjusting devices;

Fig. 2 is a plan of the tracking mechanism immediately below the spool;

Fig. 3 is a front elevation of the left hand cheek block of Figs. 1 and 2;

25 Fig. 4 is a plan of another style;

Fig. 5 is a front elevation of the same;

Fig. 6 is an end elevation of one of the pneumatics;

30 Fig. 7 is a plan of certain details of Fig. 4, showing them separated for the sake of clearness;

Fig. 8 is a plan of the principal parts of the tracking mechanism of a third style;

Fig. 9 is an elevation of the same;

35 Fig. 10 is a section on the line 10—10 of Fig. 8;

Fig. 11 is an elevation of a modified detail;

40 Fig. 12 is a diagram illustrating the operation.

Referring first to the embodiment of the invention illustrated in Figs. 1 to 3, the left hand cheek block 1 and the right hand cheek block 2 are connected at the back by a plate

45 forming a box which is open at the front. In the upper part of the box there is carried a driving shaft 4 and in line with this at the left is a free shaft 5 pressed inward by a spring 6 and having on its inner end a conical head 7 adapted to fit in a socket in the left hand head 8 of a spool which carries the perforated note sheet 9.

At the opposite end of the spool is a head 10 with a squared socket adapted to be en-

gaged by the squared end of the shaft 4. 55 This shaft is freed during the playing of a piece of music so as to permit the sheet to be drawn down by the usual feeding or winding-on roll. Thereafter the shaft 4 is clutched to a driving gear indicated di- 60 grammatically at 4^a which rotates it in the backward direction to re-wind the note sheet on the spool. Intermediate between the two rolls is a tracker-bar 11 over the face of which the sheet is drawn. It is important 65 that the sheet travel so as to bring the perforations therein in line with the perforations in the tracker-bar, and numerous devices for ensuring this correct tracking have been designed. 70

Some of these work by edge control, a finger along which the edge of the sheet travels being used to control the pneumatic adjusting mechanism; and others by surface control, the margin of the sheet passing directly 75 over a special part in the tracker-bar which controls the regulation of the pneumatic adjusting mechanism.

I have illustrated my present invention as an edge control mechanism, which has an advantage in permitting the use of stationary ports although the contact fingers are movable according to variations in the music sheet; but certain features of the invention may also be applied in connection with surface control. 80 85

On the outside of the left hand cheek block 1 is mounted a pair of pneumatics. The forward pneumatic 12 acts on the control devices at both sides and the rearward one 13 acts on the spool and the sheet carried thereby. 90

The pneumatic 12 has a small port or bleedhole 14 (Fig. 3) communicating with a pipe 15 which leads to the suction reservoir of the instrument. The suction tends to collapse the pneumatic, and a spring 16 tends to expand it. A port 17 also communicates with the interior of this pneumatic and is connected by a tube 18 (Fig. 2) with a bent tube 19 at the opposite side of the box; the left hand end of which may be opened or closed by means of a tracker valve 20 carried on a lever or finger 21 which is pivoted at 22 and the forward edge of which is adapted to bear on the right hand edge of the sheet. 95 100 105

The rear pneumatic 13 has a bleed-hole 23

communicating through a tube 24 with the suction mechanism of the instrument and has a port 25 which is connected by means of a flexible tube 26 with a fixed elbow 27, 5 the right hand end of which constitutes a port adapted to be opened or closed by means of a valve 28 on the inner end of a lever or finger 29 which is pivoted at 30 and has its outer end adapted to bear on the 10 left hand edge of the sheet.

The support on which the finger 21 is pivoted consists of an arm 31 having its rear end fastened at 32 on a support block 33 and being flexible and pressed inward by means of 15 a light leaf spring 34. Similarly the finger 29 is pivotally mounted on an arm 35 having its rear end fastened at 36 on a block 37. A spring 38 between the right hand finger and its supporting arm presses the valve 20 to its closing position and a similar spring 39 performs the same function for the left hand finger. The blocks 33 and 37 are separately mounted on a bar 11^a in the plane of and behind the tracker bar 11. Also mounted 25 on this bar 11^a are plates 11^b forming supports or wearing plates on which rest the flexible arms 31 and 35 which carry the fingers.

The movable leaf of the pneumatic 13 is 30 connected by means of a rod 40 at the back of the box, having a turn-buckle 41 by which its length may be adjusted, with the rear end of a lever 42 the forward end of which bears against the right end of the 35 shaft 4. A spool containing a note-sheet is inserted by pressing back the pin 5 at the left and bringing the ends of the spool into engagement with the pin 5 and the operating shaft 4 respectively. The spring 6 then 40 holds the spool to the right with the end of the operating shaft 4 against the forward end of the lever 42.

If the sheet tracks out of line to the left it 45 presses outward the forward end of the finger 29 and removes the valve 28 from the open end of the tube 27 and admits air to the pneumatic 13. The usual spring within the latter moves its movable leaf outward which causes the rod 40 to move to 50 the left and the forward end of the lever 42 to move to the right causing the sheet to be moved by its spring to the right until the inaccuracies are corrected. Whereupon the 55 finger 29 following the edge of the sheet closes the valve 28 and the suction within the pneumatic 13 tends to close it sufficiently to maintain the edge of the sheet in correct position against the finger.

The pneumatic 12 acts, not on the sheet, 60 but on the two tracking control fingers to move them simultaneously toward or away from each other. On the forward edge of the movable leaf of this pneumatic 12 there is a pin 43 passing through a slot in a rod 65 44 and clamped at any desired position of

adjustment in such slot. The rod 44 is pivotally connected to an ear 45 on the outer end of the arm 35 which carries the left hand finger 29. At its right hand end the rod 44 is connected to the forward end of 70 a lever 46 the rear of which bears against an ear 47 on the arm 31 which carries the right hand finger. Turn-buckles 48 and 49 serve to adjust the position of the rod 44 with respect to the right and left hand fingers. 75

By these adjustments the normal or starting position of the two fingers with respect to each other is adjusted manually.

As explained above, the left hand edge of 80 the sheet is automatically held against the left hand finger. If now a sheet of unusual width is used its right hand edge will force the end of the finger 21 outward, which will open the valve 20 and admit air through 85 the tube 18 to the pneumatic 12; so that the latter will be expanded by its spring and will pull the rod 44 to the left. This will pull the bearing of the finger 29 and the finger itself to the left and the left hand edge of the sheet will follow it. At the same time the pneumatic 12 will push the pivot of the right hand finger 21 to the right until, notwithstanding the position of the right hand edge of the paper, the valve 90 20 will close. This separating movement of the two fingers will take place to an equal extent and to a sufficient extent to adjust them to the extra width of the paper. The center line of this extra wide sheet will, 95 therefore, coincide with the center line of a sheet of normal width and the wider sheet will track correctly. If a sheet narrower than the normal width is put into the machine, the arms carrying the two fingers will, 100 by the suction in the pneumatic 12, be moved inward through equal distances toward each other so as to centralize themselves and maintain correct tracking by means of the 105 pneumatic 13 as first explained. 110

Thus we have an automatic centralizing of the fingers with respect to sheets of different widths by means of one of the edge control devices, and an automatic tracking or correct running of the sheet by means of the 115 other edge control device. It is advantageous to move the fingers or control devices in one of these automatic adjustments and to move the sheet in the other. But the essential thing is to secure the correct lateral register of the sheet with the tracker-bar and the invention may be applied to a movement of the latter instead of the sheet and tracking devices. 120

Various other arrangements of mechanism 125 may be adopted for securing the operations stated and I have illustrated two such variants in Figs. 4 to 7 and Figs. 8 to 10 respectively.

Referring to Fig. 4, the fingers 21 and 29 130

are mounted on arms 31 and 35 substantially as in the previous figures. The open tube 19 at the right is connected by a tube 18 with an outlet 50 of a pneumatic having 5 its outer leaf 51 fixed and its inner leaf 52 movable. The pneumatic has a suction port or tube 53 leading to the suction chamber of the instrument and tending to collapse it, and has a spring 54 tending to expand it. 10 The movement of the leaf 52 is transmitted through a link 55 to the lower end of a lever 56 pivotally mounted at 57 on the fixed leaf 51 and connected at opposite sides of the pivot and at equal distances therefrom to 15 links 58 and 59. The former link includes a turn buckle 60 by which it is adjustable in length and is pivotally connected at its inner end to the arm 35 which carries the finger 29. The latter is pivoted on the arm 20 35 and by means of a spring 61 is pressed in a direction to close the valve 28. The link 59 leads to the opposite side of the box and, through a turn buckle 62 to the arm 31 on which the finger 21 is pivotally connected, 25 with a spring 63 tending to hold the valve 20 closed. Besides the individual manual adjustments through the turn buckles 60 and 62 there is a third adjustment which serves to move both the links 58 and 59 to 30 the right or both to the left. To secure this adjustment the fixed leaf 51 of the pneumatic is mounted at its lower end on arms 51^a which are pivoted on an extension from the cheek block 1 and is pulled to the right by means of a spring 64 or pressed to the 35 left by means of a screw 65 passing through a nut 66 fixed on the outer face of the block, the end of the screw engaging a flange 67 on the leaf 51.

40 If now the sheet is of such width as to press the finger 21 outward and open the valve 20, air will be admitted to the pneumatic and it will expand throwing the movable leaf 52 to the right and moving the forward ends of the two fingers 21 and 29 outward, away from each other, to accommodate the increased width of paper; this movement being sufficient to cause the closing of the valve 20 and the maintaining of 45 the pneumatic in a balanced condition with the two fingers engaging the edges of the sheet.

The pneumatic 68 has a port 69 leading to the suction chamber of the instrument and 50 has a second port 70 leading through a tube 71 to the tube 27 which is closed by the valve 28. The movable leaf 72 of this pneumatic is connected by a rod 73 of adjustable length to a lever 74 which acts on the shaft 60 4 of the music spool as described in connection with the apparatus of the previous figures.

If now the sheet tracks out of line to the left it will open the valve 28 and permit an 65 expansion of the leaf 72 of the pneumatic

which will cause the sheet to be shifted to the right until the pneumatic becomes balanced.

In Figs. 8, 9 and 10 there is the same arrangement of valves 20 and 28 on fingers 21 70 and 29 mounted on arms 31 and 35, and the pneumatic 68 has similar connections to the left hand valve and to the spool shaft.

The lower pneumatic has connections to the right hand valve the same as in Figs. 1, 75 2 and 3. Its movable leaf, however, is connected by a slightly different mechanism to the two arms carrying the opposite fingers. A bent rod is pivoted on the movable leaf 12, constituting an upper rod 75 for connection with the left hand finger support and a lower rod 76 which at its right hand end is pivoted to a lever 77, the opposite end of which is connected through a rod 78 with the support for the right hand finger. In 80 other respects the construction of Figs. 8, 9 and 10 is substantially like that of the previous figures and the operation is the same.

The automatic mechanism described will 90 take care of varying width of a sheet or of differences in width between different sheets and will compel the center of the sheet to run true along the center line between the controlling fingers 21 and 29. These fingers 95 are adjusted to a normal spacing or distance apart and to equal distances from the center line of the tracker-bar by means of turn-buckles 48, 49 of Fig. 2, and the similar devices of the other figures.

100 But it happens sometimes that the perforations in the sheet are not centralized with reference to its edges. In that case, though the edges are controlled by the automatic devices as described, the perforations in the sheet will all be a little to the right or a little to the left of the corresponding openings in the tracker-bar. The adjusting screw 65 (Fig. 5) permits the user to make the necessary adjustment when such a sheet is 110 encountered. With this screw he will adjust the controlling fingers 21 and 29 both to the right or both to the left; and the sheet, following a central path between these fingers, 115 will then track truly with relation to the tracker-bar.

The same adjustment of the two fingers to the right or to the left may be effected by the adjusting screw 43 of Figs. 1^a and 2. But this is intended primarily for shop adjustment, to bring the center line between the fingers in register with the center of the tracker-bar, which is sufficient for all except such imperfectly punched sheets as I have 120 described.

In fact it is not essential, though preferable for simplicity, to have a special device for such an adjustment. By means of the turn-buckles 48, 49 in Fig. 9, for example, the fingers may be set independently to the left 125

or to the right sufficiently to secure the proper space between them and to also centralize them with respect to the tracker-bar, or to an off-center sheet.

5 Various other means may be provided for securing these adjustments. Fig. 11, for example, shows the ends of the rods 75 and 76 passing through a bar 79 which is pivoted on the movable leaf 12 of the pneumatic, the 10 rods being adjustable in the bar 79 and held therein by means of set screws 80. Also these bars may be made adjustable in length by providing them with bends 81, 82 which can be pinched together or spread in order 15 to shorten or lengthen the rods.

The action of the mechanism is indicated in Fig. 12 which shows four different positions thereof. The starting position is shown at A, before commencing to operate 20 the instrument. The tracking control devices 21 and 29 are held apart by the spring in their controlling pneumatic, the space between them being equal to or greater than 25 that of the widest sheet which is provided for. The tracking control devices are equidistant from a center line 83. The sheet 9 is held in its extreme right hand position by the spring on its controlling pneumatic. When the fingers 21 and 29 are in position 30 to close their ports they are represented in solid black, when in the opposite position, in outline.

As soon as the operator commences to 35 pump, the suction is transmitted to both pneumatics. The supports for the fingers 21 and 29 will be drawn inward equally toward the line 82. At the same time the sheet 9 will be shifted to the left. These 40 two movements will continue until the sheet is centralized, as in position B, and the two fingers are brought to bear slightly against the opposite edges thereof. This is the regular running position in which the ports controlled by the two fingers are slightly 45 opened, just sufficiently to supply air to the pneumatics at the same rate at which it is sucked out from the pneumatics.

If the sheet is deflected to the left, as in 50 position C, the finger 29 will be deflected to open its port wide. The finger 21 will close its port, and there will result a shifting of the sheet to the right and an inward pressure on the two controlling devices until the parts again assume the regular position, B.

55 If on the other hand the sheet shifts to the right as in position D, the port controlled by the finger 29 will be closed and will cause a section in the corresponding pneumatic which will shift the sheet to the left. The 60 port controlled by the finger 21 will have been opened wide so as to cause a separation of the supports for the fingers, but the moving of the finger 21 out of contact with the edge of the sheet will cause the closing of its 65 port, and the same effect will be caused by

the movement of the sheet to the left away from the finger 21. There will, therefore, be an inward pressure upon the two controlling devices and the sheet will come to the central position shown at B, with the two fingers 70 bearing lightly on its opposite edges.

It will be understood that the resetting or adjusting operations described will commence to take place as soon as there is any departure from the ideal running position B 75 so that at no time will there be any substantial departure from this position.

Though I have described with great particularity in detail certain specific embodiments of my invention, yet it is not to be understood therefrom that the invention is restricted to the particular embodiments disclosed. Various modifications thereof in detail and in the arrangement of the parts may be made by those skilled in the art without departure from the invention as defined in the following claims.

What I claim is:

1. A tracking mechanism including in combination a pair of tracking-control fingers co-operating with fixed ports and with opposite sides of the sheet and automatic means for adjusting said fingers toward or away from each other. 90

2. A tracking mechanism including in combination a pair of tracking-control fingers cooperating with fixed ports and with opposite sides of the sheet, means for adjusting them toward or way from each other and means controlled by said fingers for maintaining correct adjustment of the sheet 100 with relation to the tracker-bar. 95

3. A tracking mechanism including in combination a pair of tracking-control devices on opposite sides of the sheet, means for adjusting them toward or away from each other, and means for adjusting them together to the right or to the left. 105

4. A tracking mechanism including in combination tracking-control devices at opposite sides of the sheet, means controlled by one of said devices for adjusting their distance apart to the width of the sheet and means controlled by the other of said devices for maintaining the correct tracking of the sheet, and means for manually adjusting the spacing of said devices from each other. 110

5. A tracking-control mechanism including in combination a pair of tracking devices and means for adjusting them toward or away from each other automatically under control of the sheet and means for manually adjusting said devices together to one side or the other. 120

6. A tracking-control mechanism including in combination a pair of tracking devices and means for adjusting them toward or away from each other automatically under control of the sheet, means for manually adjusting said devices together to one side 125 130

or the other and means for manually adjusting the spacing of said devices from each other.

7. A tracking mechanism including in combination tracking-control fingers co-operating with fixed ports and with the edges of the sheet, each finger mounted upon an independent support, and means for adjusting said supports to vary the spacing of 10 said fingers from each other.

8. A tracking mechanism including in combination tracking-control fingers co-operating with fixed ports and with the edges of the sheet, means for holding said fingers

apart and automatic means for moving them 15 toward each other when the instrument is operated.

9. A tracking mechanism including in combination tracking-control fingers co-operating with fixed ports and with the edges 20 of the sheet, means for holding said fingers apart and means actuated automatically upon an incorrect tracking of the sheet for causing an inward pressure on said fingers and a centralizing movement of the sheet. 25

In witness whereof I have hereunto signed my name.

REINHOLD BUKOW.
